SHOE INSOLE

Lucien M. Doty and Norval B. Griffin, Portsmouth, Ohio, assignors to The Selby Shoe Company, Portsmouth, Ohio, a corporation of Ohio

Application August 20, 1932. Serial No. 629,652

1 Claim. (Cl. 36—71)

Among the principal objects which the present invention has in view are: To support the inner side of the longitudinal arch of the human foot; to correct any tendency that the foot may have to roll inwardly; to improve the appearance of the shoe; to provide a support for the metatarsal arch of the human foot, and to provide a better foundation of the heel portion of the insole for attaching the heel to the shoe.

10

Drawing

Figure 1 is a side view of a shoe partly in section showing the disposition and arrangement of an insole constructed and arranged in accordance with the present invention.

Figure 2 is a top view of the insole.

Figure 3 is a cross section thereof, the section being taken as on the line 3—3 in Figure 2.

20

Description

The insole for a shoe when constructed in accordance with the present invention comprises a body layer 8 of relatively thickened material. This material may be of leather or textile. It is preferably covered with a thin leather sock-lining 9. At a certain point, in line preferably with what might be termed the bend of the wear-sole, a pad 10 is disposed between the body layer 8 and the sock-lining 9. The pad 10 serves as a support for the metatarsal arch of the foot and is placed in accordance therewith.

The insole is shaped to provide a lateral extension 11. This extension 11 is preferably raised to the position substantially as shown in the drawing. The extension is held in shape by a shank stiffener 12, preferably constructed of stiff, or so-called counter leather, which extends upward from the contour of the insole to form a support for the said extension. This construc-

40

tion can be best seen in Figure 3 of the drawing. The longitudinal edges of the stiffener 12 are skived or pared thin at the outer edges.

Longitudinally the combined structure of the insole and the shank stiffener 12 are reinforced by a shank iron 13. The shank iron 13 is rigidly secured by pegs or tacks to the combined construction. The shank stiffener 12 is permanently attached to the body 8 of the insole by any suitable adherent, and is extended back to form in conjunction with said body a heel seat of added strength, while assisting in attaching the structure to a heel.

By employing an insole having the above described shank stiffener and shank iron, the said stiffener extending out and under the extension 11 to give support thereto, the shoe structure is strengthened and the supporting features thereof are efficient, yet yielding to avoid hurting the sensitive muscles in the under portion of the instep at the inner side of the foot.

We claim:

An insole for a shoe, comprising a body portion having a lateral extension conforming to the inner under side of the human foot to support the same; a shank stiffener constructed of semi-stiff material and having a lateral extension conforming with and disposed under the extension of said body portion, the body portion and said shank stiffener being permanently adhered; a shank iron attached to said body portion and said shank stiffener at the forward and rear ends thereof, and a pad disposed on said body portion adjacent the location of the metatarsal arch of the human foot, said pad being held in position by a sock-lining mounted upon said body portion.
